CONVERTIBLE DOORSTOP

Gotthard Hagstrom, Berlin, Conn., assignor, by
mesne assignments, to Pet-Car Grinding Co.,
New Haven, Conn., a firm

Application November 3, 1944, Serial No. 561,768

4 Claims. (Cl. 16—86)

1

The present invention relates to improvements in doorstops, and relates more particularly to convertible doorstops of a type which may be converted for use either vertically or horizontally.

The main object of the present invention is to provide a superior doorstop having elements so constructed and arranged as to be readily converted for use either in a vertical position (as when mounted upon a floor or the like) or for use in a horizontal position (as when mounted on a baseboard or the like).

Another object of the present invention is to provide a superior convertible doorstop combining convenience and reliability in use with low cost for manufacture.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a top or plan view of a convertible doorstop embodying the present invention and shown with the parts in position to act as a doorstop when mounted upon a floor or the like;

Fig. 2 is a view thereof in side elevation;

Fig. 3 is a view thereof in rear elevation;

Fig. 4 is a vertical central sectional view taken on the line 4—4 of Fig. 1;

Fig. 5 is a view partly in side elevation and partly in the central section of the head-member detached;

Fig. 6 is a similar view of the body-member detached;

Fig. 7 is a view in side elevation showing the body-member and head-member turned relative to each other to function in a horizontal position;

Fig. 8 is a view partly in side elevation and partly in vertical central section of another form of convertible doorstop embodying the present invention; and

Fig. 9 is a sectional view thereof taken on the line 9—9 of Fig. 8.

The structure of Figs. 1 to 7 inclusive

The convertible doorstop illustrated in Figs. 1 to 7 inclusive of the accompanying drawings, includes a body-member 10, a head-member 11 and a clamping-screw 12.

The body-member 10 includes a relatively broad base-portion 13 from which extends a tapering shank 14 surmounted by an integral

2

substantially-hemispherical portion 15 having an oblique clamping-face 16 which, in the instance shown, is disposed obliquely at an angle of 45° with respect to the base-portion 13.

The head-member 11 includes a substantially-hemispherical portion 17 having a clamping face 18 adapted to engage with the clamping-face 16 of the body-member 10. The said head-member also includes an integral neck 19 projecting obliquely with respect to the clamping-face 18. In the instance shown, the clamping-face 18 is disposed at an angle of 45° with respect to the longitudinal axis of the neck 19, while the latter has mounted on its outer end a buffer 20 which may be formed of any suitable resilient material such, for instance, as rubber.

Formed in the hemispherical-portion 17 of the head-member 11 and extending centrally in a direction perpendicular with respect to the clamping-face 18 is a threaded socket 21 extending in axial alignment with respect to a clearance-passage 22 formed in the hemispherical-portion 15 of the body-member 10. The clearance-passage intersects the clamping-face 16 of the hemispherical-portion 15 just referred to, and the opposite end of the said clearance-passage is enlarged to provide a recess 23 for the accommodation of the head of the clamping-screw 12. The clamping-screw freely fits the clearance-passage 22 in the hemispherical-portion 15 of the body-member 10, but has threaded engagement with the threaded socket 21 in the hemispherical-portion 17 of the head-member 11, and serves to firmly clamp the clamping-face 18 of the said head-member 11 against the clamping-face 16 of the body member 10.

Preferably and as shown in Fig. 4, the body-member 10 is formed with a threaded socket 24 extending coaxially within the shank 14 and intersecting the outer face of the base-portion 13. A mounting-screw, bolt or other suitable fastening-device may be threaded into the socket 24 to mount the convertible doorstop in any desired position.

In Figs. 1 to 4 inclusive, the body-member 10 is shown in the position which it might assume if mounted upon a floor surface, while the head-member 11 is turned so that its neck 19 and hence its buffer 20 project perpendicularly with respect to the body-member 10 and hence horizontally in a position to act as a stop for a door or the like.

By loosening the clamping-screw 12, the head-member 11 may be reoriented relative to the body-member 10 and brought, for instance, into

the position indicated in Fig. 7, following which the clamping-screw would be again tightened. As illustrated in Fig. 7, the convertible doorstop is suitable for use in a horizontal position such, for instance, as by having its base 13 secured against the face of a baseboard, under which conditions the buffer 20 is in position to act as a stop for a door or the like.

The structure of Figs. 8 and 9

The convertible doorstop illustrated in Figs. 8 and 9, includes a body-member 25, a head-member 26 and a clamping-screw 21.

The body-member 25 includes a base-portion 28, a shank 29, and a hemispherical-portion 30 at the end of the shank 29 opposite from which the base-portion 28 is located. The hemispherical-portion 30 just referred to, is formed with an obliquely-disposed clamping-face 31 against which is located a spacing-washer 32. Arranged centrally and perpendicularly with respect to the clamping-face 31, is a clearance-passage 33 which extends through the hemispherical-portion 30 of the body-member 25. The said clearance-passage 33 is enlarged at its end opposite the clamping-face 31 to provide a recess 34 for the accommodation of the head of the clamping-screw 21.

The head-member 26 also includes a substantially-hemispherical portion 35 having an obliquely-disposed clamping-face 36 adapted to be clamped against the adjacent face of the spacing-washer 32. The head-member is also formed with a threaded socket 37 threadedly receiving the end-portion of the clamping-screw 21.

Like the head-member 11 before referred to, the head-member 26 is provided with a neck 38 having its axis extending at about 45° with respect to the plane of the clamping-face 36 and mounting a buffer 39 formed of rubber or other suitable resilient material.

The diameter of the spacing-washer 32 preferably substantially-corresponds to the respective diameters of the clamping-faces 31 and 36 so as to complement the contours of the portions 30 and 35. The spacing-washer 32 is formed with an eccentrically-located eye-portion 41 in which is pivoted the inner end of a hook 42, which latter may be utilized to hold a door or the like in an open position. The spacing-washer 32 and its eye-portion 41 may be turned in any desired position to permit the hook 42 to accommodate itself to the requirements of various situations. If no hook 42 or the like is desired, the spacing-washer 32 may be replaced by a plain circular washer.

General

From the foregoing, it will be seen that a head-member may be turned with respect to a body-member to enable the doorstop to be converted for uses in various positions.

While, as above described, a given head-portion has been shown either as extending at a right angle with respect to a given body-member or as extending in parallelism therewith, many intermediate positions of a given head-member with respect to a given body-member may be utilized to accommodate the convertible doorstop to meet requirements of many different types of installations.

The invention may be carried out in other specific ways than those herein set forth without departing from the spirit and essential characteristics of the invention, and the present em-

bodiments are, therefore, to be considered in all respects as illustrative and not restrictive, and all changes coming within the meaning and equivalency range of the appended claims are intended to be embraced therein.

I claim:

1. A convertible doorstop, including in combination: a body-member having a base-portion and a clamping-face extending obliquely with respect to the said base-portion; a head-member having a buffer and a clamping-face extending obliquely with respect to the said buffer the second oblique clamping-face being arranged to cooperate with the oblique clamping-face of the said body-member and to rotate thereon with respect thereto; and a connector associated with said head-member and said body-member comprising clamping-means constructed and arranged to permit said head-member to rotate relative to said base-member and to draw the respective clamping-faces of the said head-member and the said body-member toward each other to interlock the two said members together in any one of a plurality of relative positions.
2. A convertible doorstop, including in combination: a body-member having a base-portion and a clamping-face extending obliquely with respect to the said base-portion; a head-member having a buffer and a clamping-face extending obliquely with respect to the said buffer the second oblique clamping-face being arranged to cooperate with the oblique clamping-face of the said body-member and to rotate thereon with respect thereto; and a connector associated with said head-member and said body-member comprising a clamping-screw extending between the two said members in a direction substantially perpendicularly with respect to the respective clamping-faces thereof and constructed and arranged to permit said head-member to rotate relative to said base-member and to draw the respective clamping-faces of the said head-member and the said body-member toward each other to interlock the two said members together in any one of a plurality of relative positions.
3. A convertible doorstop, including in combination: a body-member having a shank, a clamping-face extending obliquely with respect to the longitudinal axis of the said shank and an aperture; a head-member having a buffer, a clamping-face extending obliquely with respect to the said buffer and an aperture, the second oblique clamping-face being arranged to cooperate with the oblique clamping-face of the said body-member and to rotate thereon with respect thereto; and a pivotal connection between said head-member and said body-member comprising a clamping-screw secured in the apertures of the two said members and extending between the two said members in a direction substantially perpendicularly with respect to the respective clamping-faces thereof and constructed and arranged to permit said head-member to rotate relative to said base member and to draw the respective clamping-faces of the said head-member and the said body-member toward each other to interlock the two said members together in any one of a plurality of relative positions.
4. A convertible doorstop, including in combination: a body-member having a base-portion and a clamping-face extending obliquely with respect to the said base-portion; a head-member having a buffer and a clamping-face extending obliquely with respect to the said buffer the sec-

ond oblique clamping-face being arranged to co-operate with the oblique clamping-face of the said body-member and to rotate thereon with respect thereto; a spacing-washer interposed between the respective clamping-faces of the said body-member and the said head-member; and a connector associated with said head-member and said body-member comprising clamping-means constructed and arranged to permit said head-member to rotate relative to said base-member and to draw the respective clamping-faces of the said body-member and the said head-member toward each other to grip the said spacing-washer therebetween to thus interlock

the two said members together in any one of a plurality of relative positions.
